UNITED STATES PATENT OFFICE.

ALBERT J. BATES AND JOHN A. COCKER, OF JOLIET, ILLINOIS, ASSIGNORS
TO THE AMERICAN STEEL & WIRE COMPANY OF NEW JERSEY, A COR-
PORATION OF NEW JERSEY.

WIRE-FENCE MACHINE.

SPECIFICATION forming part of Letters Patent No. 732,155, dated June 30, 1903.

Application filed January 19, 1903. Serial No. 139,618. (No model.)

To all whom it may concern:

Be it known that we, ALBERT J. BATES and JOHN A. COCKER, both citizens of the United States, residing at Joliet, county of Will, State of Illinois, have invented certain new and useful Improvements in Wire-Fence Machines; and we do hereby declare the following to be a full, clear, and exact description of the invention, such as will enable others skilled in the art to which it appertains to make and use the same.

The object of the present invention is to improve the machines of the patents granted to A. J. Bates February 23, 1897, No. 577,639, and October 19, 1897, No. 591,996, for machines for making wire fencing in respect of the manner of and means for delivering the product of the machines from the coiling and crimping mechanisms to the drums whereon it is wound ready for the market. In the machine of the first of these patents there is interposed between the winding-drum and the coilers a series of feeding-rolls which pull the fabric through the machine and keep it under the necessary tension until the completed roll is wound on the winding-drum.

In the present improvement there is a particular construction of feed-roll employed; but instead of operating it intermittently, as before, it is continuously rotated, and there is interposed between it and the coilers a certain take-up device producing the necessary intermittent movement of the strand-wires through the coiling and crimping mechanisms of the machine. Otherwise than as relates to this feed-drum and take-up device the construction contemplated by the present invention is the same as in the former patents, except certain modifications in the gearing and shafting, made necessary by the above-described difference in the manner of driving the parts, all of which will be described later on. Only so much of the machines of the former patents will therefore be illustrated and described herein as is necessary to an understanding of the new arrangements for handling the fencing as it comes from the coilers. These improvements are illustrated in the accompanying drawings, wherein—

Figure 1 is a side elevation of the whole

machine, and Fig. 2 is a plan view thereof. Fig. 3 is a horizontal section of the entire machine on the line 3 3 of Fig. 1. Fig. 4 is a sectional elevation of the take-up device, and Fig. 5 is a horizontal section of the same on the line 5 5 of Fig. 4. Fig. 6 is an elevation of the feed-roll, and Fig. 7 is a vertical section of the same on the line 7 7 of Fig. 8, which latter is a horizontal section of the roll. Fig. 9 is a plan view of the top plate of the roll, and Figs. 10 and 11 are details of the crimper-bar of the roll.

Referring first to Figs. 1 and 2, the main shaft *a* drives a counter-shaft *b*, which in turn is geared to a short shaft *c*, that is parallel therewith and carries a pinion *5*, from which power is taken to operate those parts of the machine to which the present invention relates. The shaft *c* also carries certain cams, cranks, and eccentrics for distributing power to other parts of the machine; but as they are not particularly involved in the present invention no description thereof is deemed necessary. Power from the shaft *c* is carried to a line-shaft *e*, journaled lengthwise the machine above its top plate, through the train of gears 1 2 3 5. (Best shown in Fig. 2.) The shaft *e* is therefore continuously rotated and drives the feed-roll, already referred to, by means of the bevel-wheel *f* and also operates the take-up device by the similar wheel *g*, the shaft *h* of the feed-roll having a gear *i* meshing with the wheel *f* and the shaft *j* of the take-up device having a bevel-pinion *k* gearing with the wheel *g*. The office of the feed-roll is to pull the completed fencing through the machine and keep it under the proper tension until it is coiled up on the winding-drum, which is denoted by *l* in Figs. 2 and 3 and is the same as in the patents above referred to. The roll is therefore located a little to one side of the line of strand-wires as they come from the coilers, guides *m* and a roller *n* being located and arranged to preferably direct the strand-wires onto the surface of the roll in line with the gripping devices, to be presently described. The feed-roll is formed of a shell *o*, clamped between heads *p* and *q*, that are rigidly secured on the shaft *h*. The shell is grooved longitudinally at in-

tervals around its periphery, and in these grooves are secured bars r r , of hardened steel, that are notched transversely at intervals corresponding to the spaces between the 5 strand-wires of the fencing. Between these two fixed bars r r in each of the grooves of the roll there is arranged a sliding bar s , also of hardened steel and having notches corresponding in shape and position to those first 10 mentioned. The fixed bars r r are just equal in length to the shell of the roll; but the sliding bars are longer and project through open-ended slots t in the head-plates p and q and are held in place and kept from falling 15 out by keepers u , that are secured at appropriate intervals along the roll. The circumference of the feed-roll is thus, in effect, provided with grooves to receive the strand-wires, and the object of making the bars s 20 movable is to provide grips for seizing and crimping the wires before they pass onto the winding-drum. As the fencing passes through the machine the strand-wires are guided into these grooves by the guides and roller m n , 25 before referred to, and as they enter the notches in the fixed bars r r the sliding bars are operated so as to bend and crimp the wires, as best illustrated in Figs. 10 and 11. In order to effect this movement of the 30 notched bars s , the upper and lower ends of the roll are provided, respectively, with rollers v and w , which strike the ends of the bars projecting beyond the heads p and q and push them up or down, as the case may be, so as 35 to cause their notches to register or not with the notches of the fixed bars. The roller w is located at a point in the revolution of the roll near where the wires first engage the surface of the roll, and as the notches in all the 40 bars coincide at this time, so as to form open grooves, the lower ends of the bars s project below the head q ; but as the feed-roll rotates they strike the upper edge of the roller w and are pushed upward, so that their notches are 45 out of registration with the notches of the fixed bars, and they are thus made to grip the wires and form crimps in them, as shown in Figs. 10 and 11. After the ends of the bars leave the roller w they slide onto a semicircular track x , which extends from the roller about one-third the way around the roll or to a point in its revolution where it is desired to release the wires. After the wires are 50 released and leave the roll the upper ends of the bars s are struck by the roller v , which pushes the bars downward in the opposite direction, so as to cause all the notches to open, so as to receive the uncrimped ones coming from the guides m . In this way the feed-roll 55 is not only made to take a firm hold on the wires, so as to pull the fencing from the take-up, but the strand-wires are at the same time given the crimps which it is desirable all fencing should have in order to allow for such 60 shrinking and stretching as may be due to strains when the fences are being put up or to subsequent changes in temperature.

As before described, the feed-roll is continuously rotated, and as some of the grips always have hold of the wires that part of the 70 fencing immediately in front of the roll must also move continuously. The fencing leaves the coilers, however, intermittently, as will be understood when it is considered that the strand-wires must stop and remain at rest 75 while the stays are being coiled around them, and the office of the take-up device, which will now be described, is to form a loop or bight on the fencing as it comes from the coilers, so that the extra length of fabric thus 80 stored up between the coilers and the feed-roll will be sufficient to allow the roll to keep on moving during the intervals when the coilers are at work. This take-up is best illustrated in Figs. 4 and 5. It consists of a roller 85 a' , journaled at its opposite ends in bars or arms a^3 , that are pivoted at their opposite ends to some fixed part of the machine. These arms are also pivotally connected to the straps a^4 and a^5 of a pair of eccentrics a^6 a^7 , which are 90 respectively fixed near the lower and upper ends of the take-up shaft j , before referred to. The fencing as it passes from the coilers travels against the guide-roller a^8 , and the take-up shaft j is located about midway between 95 this roller and another guide-roller a^2 , located at the entrance to the guides m . On its way between these points the fabric passes on one side of the roll a' , and the eccentrics a^6 a^7 are 100 so fixed on the shaft that they project the roller across the path of the wires immediately after each operation of the coilers. The fencing and the position of the moving parts at this juncture are illustrated in Fig. 5. At this time it is necessary to move the whole 105 fabric forward a distance equal to the space between the stays, and the revolution of the take-up shaft j is so timed with respect to the coilers that it pushes the roller against the fencing as soon as the strand-wires are free 110 to be pulled through the coilers, and the eccentrics and arms a^3 are proportioned so that this movement of the roller will pull the wires forward at a rate of speed double that of the feed-roll. This causes a deflection of the 115 fencing between the guide-rollers a^2 and a^8 , as shown in Fig. 3, thereby storing up the surplus length until the rotation of the eccentrics pulls the roller a' back again, when the slack of the fabric is taken up by the 120 feed-roll. This return movement of the eccentrics occurs when the coilers are in operation and when, of course, the strand-wires cannot be drawn through them, and the effect is to permit the feed-roll to revolve at a 125 continuous rate of speed, though the strand-wires and the coilers and all the other mechanism of the machine operate intermittently. The speed of the feed-roll's rotation may be regulated with respect to the action of the 130 take-up in any way desired. As here shown, the take-up pulls the strand-wires through the coilers at twice the speed of the roll, and the throw of the eccentrics is proportioned so

as to take up just enough of the fabric to keep the roll going during the succeeding operation of the coilers.

The invention is not limited to the construction of the take-up or the feed-roll herein illustrated, and any other construction of those devices might be employed that would do the same thing. So, also, may these devices be employed in other types of machines than that contemplated in the Bates patents, already referred to.

The coilers contemplated herein are the same as in the above patents to Bates. They are located at a^9 , and their pinions a^{10} are operated by reciprocating gear-racks b^8 , which may be constructed and operated in any way suitable to produce an intermittent rotation of the spindles. It is to be particularly understood, however, that the present invention is not limited to any particular construction or mechanism for operating these coilers.

Having thus described our invention, what we claim is—

1. In a wire-fence machine, the combination of a continuously-operating feed-roll, intermittently-operating coilers, and a take-up located between the coilers and the roll for pulling the strand-wires through the coilers at a speed greater than required by the feed-roll.

2. In a wire-fence machine, the combination of a continuously-operating feed-roll, intermittently-operating coilers, and a take-up located between the coilers and the roll for pulling a sufficient length of strand-wires through the coilers when they are at rest to supply the rotation of the feed-roll during the next operation of the coilers.

3. In a wire-fence machine, the combination of the winding-drum, a continuously-operating feed-roll interposed between the drum and the coilers, said roll being provided with grips for seizing and crimping the strand-wires and a take-up located between the coilers and the feed-roll for pulling the strand-wires through the coilers at a greater speed than required by the feed-roll.

4. The combination to form a strand-wire crimping mechanism for wire-fence machines, of a roll provided with longitudinal notched bars, the notches thereof being alined to form peripheral grooves to receive the wires, longitudinally-sliding bars between the bars aforesaid having notches corresponding to the peripheral grooves, and mechanism for operating the sliding bars so as to grip the wires in the grooves during a part of the drum's rotation.

5. The combination to form a strand-wire crimping mechanism for wire-fence machines, of a roll provided with longitudinal bars

having lines of notches forming peripheral grooves to receive the wires, longitudinally-sliding bars between the bars aforesaid and having notches corresponding to the notches therein, mechanism for moving the sliding bars in one direction to make its notches correspond with those of the other bars and thereby open the grooves, and mechanism for moving the bars in the opposite direction to cause them to grip and bend the wires.

6. In a feed-roll for wire-fence machines, the combination of the shaft h , the radially-notched heads p, q , the longitudinally-grooved shell o secured between the heads, the notched bars r, r , fixed in said grooves, the bars s sliding between the fixed bars, and means for operating the sliding bars.

7. In a feed-roll for wire-fence machines, the combination of the shaft h , the radially-notched heads p, q , the longitudinally-grooved shell o secured between the heads, the notched bars r, r , fixed in said grooves, the bars s projecting beyond the heads and sliding between the fixed bars, and rollers v, w , for operating the sliding bars.

8. In a feed-roll for wire-fence machines, the combination of the shaft h , the radially-notched heads p, q , the longitudinally-grooved shell o secured between the heads, the notched bars r, r , fixed in said grooves, the bars s projecting beyond the heads and sliding between the fixed bars, roller w and semicircular track x at the foot of the roll, and roller v at the head of the roll for operating the sliding bars.

9. A take-up for wire-fence machines, consisting of an operating-shaft j , a roller a' , located on the line of the wire, and means connecting the shaft and the roller for projecting the roller bodily across the path of the wire.

10. A take-up for wire-fence machines, consisting of an operating-shaft j , pivoted arms a^3, a^8 , a roller carried by said arms, and connections between the arms and the shaft, whereby the roller is projected across the path of the wire.

11. A take-up for wire-fence machines, consisting of an operating-shaft j , pivoted arms a^3, a^8 , a roller carried by said arms, eccentrics a^6, a^7 , on the shaft, and connections a^4, a^5 between the eccentrics and the roller-carrying arms.

In testimony whereof we affix our signatures in presence of two witnesses.
